DESIGN FOR A CURTAIN

Hugo Geller, New York, N. Y., assignor to
Patchogue-Plymouth Mills Corporation, New
York, N. Y., a corporation of New York

Application May 19, 1934, Serial No. 51,852

Term of patent 14 years

To all whom it may concern:

Be it known that I, HUGO GELLER, a citizen of the United States, residing in the Borough of Manhattan, county of New York, and State of New York, have invented a new, original, and ornamental Design for a Curtain, of which the following is a specification, reference being had to the accompanying drawing, forming part thereof.

Fig. 1 is a plan view of a curtain showing my design;

Fig. 2 is a vertical section thereof taken along the line 2—2 of Fig. 1;

Fig. 3 is a horizontal section thereof taken along the line 3—3 of Fig. 1; and

Fig. 4 is a fragmentary detailed view of the mesh, network or weave.

What is claimed is:

The ornamental design for a curtain as shown.

HUGO GELLER.
